(57) **CLAIM**

The ornamental design for an enclosed pump, as shown and described.

DESCRIPTION

FIG. 1 is a front right perspective view of an enclosed pump showing my new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

The broken lines shown in the figures are included for the purpose of illustrating portions of the enclosed pump and form no part of the claimed design.
